UNITED STATES PATENT OFFICE.

WILLIAM H. BAYNARD, OF QUINCY, MASSACHUSETTS, ASSIGNOR TO HARRY H. BECKWITH, OF BROOKLINE, MASSACHUSETTS.

SHOE HEATER.

Application filed December 12, 1921. Serial No. 521,759.

In the manufacture of shoes it is customary to incorporate therein stiffening members which may be softened by the application of heat, this softening being effected so that the 5 shoe may be properly shaped to the last. A preliminary softening operation is commonly effected before the shoe is pulled over and a subsequent softening operation after the shoe is pulled and before it is lasted. At 10 the same time that the stiffener is softened it is usual to subject the leather to a moist heat to temper it and render it more workable.

In my application Serial No. 370,384, filed April 1, 1920, is disclosed and claimed the 15 idea of utilizing a dry heat for softening the stiffener and a comparatively cool vapor for tempering the leather. The present invention relates to mechanism of the same type as disclosed in the above mentioned application 20 and has been particularly designed for use on shoes after they have been pulled over.

One feature of this invention relates to a construction by which the dry heat is conducted to the stiffener while the vapor is conducted to the upper leather, the dry heat and 25 vapor not being allowed to mingle until after they have acted on the shoe.

A further feature relates to a construction by which only a small amount of water is subjected to the vaporizer at one time so that 30 the heat required is reduced and production of vapor in large excess of actual requirements is not effected. The proportions of dry heat and vapor are also so regulated that the 35 escape of visible moisture is practically eliminated so that no stack for receiving the vapor to prevent excess moisture in the work room is necessary. This effects economy in construction and installation and makes possible 40 installation where otherwise it would be impracticable due to local conditions.

A further feature relates to automatically 45 acting means to supply water as required to the vaporizer.

Where a shoe heater is designed to treat a plurality of shoes at the same time, the 50 shoes being placed on and removed from the several treating positions in rotation so that each may remain a sufficient time to be properly softened without delaying the operator, some difficulty has been experienced in ascertaining which of the several shoes is to be removed at a particular time.

This invention, therefore, also provides 55 mechanism for indicating the particular shoe

to be removed so that the sequence of rotation may be readily followed.

Further valuable features and advantageous details and combinations of parts will appear from a description of an embodiment 60 shown in the accompanying drawings in which

Figure 1 is a front elevation of a heater.

Figure 2 is a section on line 2—2 of Figure 1.

Figure 3 is a section on line 3—3 of Figure 2.

Figure 4 is a section on line 4—4 of Figure 2.

Figure 5 is a sectional detail showing the 70 heating unit support.

Figure 6 is an end view of a unit-retaining plug.

Figure 7 is a diagram of the wiring.

Referring to the drawings, at 1 is indicated 75 a pan-shaped base for supporting the heater having posts 2 upstanding from the base portion 3 thereof for this purpose. Carried on this base is a vaporizer member comprising a trough-shaped receptacle 4 having a substantially cylindrical lower portion 5 leading upwardly to an inverted channel portion 6. Substantially centrally disposed lengthwise of the trough 5 is a substantially triangular open topped receptacle 7. The apex of this 80 receptacle is rounded and has fixed thereto a lug 10 depending from a support 11 formed as a portion of a circle and which has a marginal flange 12 at its upper edge for supporting a water reservoir comprising a substantially circular tank or bottle 13. This bottle is supported in inverted position so that its neck 14 extends downwardly within the receptacle 7. Within this neck is positioned an 85 inwardly opening valve 15 which is normally held seated against the lower face of a cover 16 closing the bottle neck by means of a spring 17 surrounding the stem of the valve and bearing against a collar 18 fixed thereto.

When in the inverted position shown, the 90 valve is held unseated by means of a screw 19 threaded in a boss 20 projecting upwardly from the base of the receptacle 7 and engaging the end of the stem. On removal of the bottle 13 the valve closes and prevents the 95 escape of water. It is evident that this construction furnishes an automatic gravity feed to the receptacle 7. At 21 is shown a pipe leading through the base of the receptacle 7 and upwardly into the cylindrical chamber 100 110

5 by which means water is fed from the receptacle 7 thereto.

The portion 6 is provided with a series of openings or ports 22 in its upper face with 5 which register similar openings in a hollow member 23 supported from the vaporizer and made fast thereto at intervals by means of bolts 24. The member 23 is formed as a series of receptacles 25 having inwardly inclined 10 side walls 26, rear walls 27 and a common top wall 28. Between adjacent walls 26 are vertical partitions 29 which meet the partitions 26 substantially at their forward edges and extend backwardly to a back wall 30 ex- 15 tending in scalloped formation the length of the member 23, and defining, together with the walls 26, 27, and 29, a series of vapor expansion chambers which communicate through the ports 22 with the portion 6. The 20 side walls 26 are provided with ports 31 through which vapor may pass from the expansion chambers into the receptacles 25.

For forming the vapor the tubular portion 5 has mounted therein a pipe 32 which at its 25 ends forms a water tight joint with the ends of the portion 5. This pipe is of sufficient size to nearly fill the portion 5 forming therewith a narrow annular chamber extending the length of the vaporizer. Positioned within 30 in this tube is a heating element of any suitable description. As shown more particularly in Figure 5 this may comprise an electric heating element having a central stem 35 to which are fixed radiating fins or plates 36. For the purpose of supporting this unit 35 in position, a plug 37 (see Figures 5 and 6) having a flange 38 engaging the inner face of the pipe 32 is slotted at 39 from its outer edge to a central opening 40 through which the 40 stem 35 may pass. Between the opening 40 and the outer end of the slot 39 is formed a perforation 41 in which may be placed a tapered pin 42. When the parts are in position as shown in Figure 5, this pin may be driven 45 inwardly to spread the plug in either direction from the slot 39 and thus wedge it into tight engagement with the pipe. The moist heat for tempering the shoe upper is produced by this heater.

50 For producing the dry heat for softening the stiffener a heating element 350 of any suitable description, but herein shown as of the same form as that used within the pipe 32, is mounted lengthwise of the member 23 extending beneath the open lower ends of the receptacle 25, the side walls of which may be cut away as shown at 44 in Figure 3 to permit this element to pass.

For the purpose of conducting current to 60 these elements their ends may be connected by means of conducting bars 45 to which may be attached the conductor wires 46. One of these wires extends within a box-shaped casing 47 at one end of the apparatus, through a 65 cover plate 48 thereon, and into a socket 49

of a lamp 50 and to a switch of any suitable description shown at 51. The other wire passes from the opposite ends of the heating units through a pipe 52 opening at one end in the casing 47 and at the other end in a casting 53 which houses the opposite ends of the units. From the pipe 52 this wire extends through the cover 48 to the light socket 49 and to the switch 51, the light 50 being shunted across the lines as shown in Figure 7.

The receptacles 25 are partially closed at their forward side by means of a cover plate 60 through which are substantially semicircular openings 61 (see Figure 1) through which the toe of the pulled over shoe may be inserted as shown in Figure 3. The shoe is supported in position by means of a suitable rack of piping or other construction 63 which may be made fast at its inner end in the base member as shown in Figure 3. The toe of the shoe 85 is then positioned substantially between the ports 31 in the side walls 26 so that the vapor is directed thereagainst. In order that the dry heat from the heating element 350 may be directed to act on the stiffener, each receptacle 25 has positioned therein somewhat below the sole of the shoe a baffle plate 65 having a marginal flange 66 by which it may be made fast to the inner walls of the receptacle and having a V shaped opening 67 95 therein to confine the escape of the heated air substantially centrally of the shoe sole so that it may impinge thereon and be deflected thereby laterally toward the inner face of the pulled over upper where it may act on the 100 stiffener.

It will thus be seen that the vapor, which is cooled by expanding in the expansion chambers back of each receptacle, passes into contact with the leather of the upper without having been affected to any extent by the dry heat arising from the element 350 and that the dry heat is directed to act on the stiffener without being laden with moisture from the vapor. With this construction the 105 leather and the stiffener are both acted on by the type of heat most suitable. After having acted on the upper, however, the dry heat and the vapor mingle within the receptacle around the shoe and in the proportion of 110 parts shown it is found that the moisture is so nearly absorbed by the dry heated air that there is practically no visible escape of moisture from the receptacles. For this reason it has been found unnecessary to provide this 115 apparatus with a stack of any description for conducting away the excess moisture as has heretofore been necessary in most cases in order to prevent an excessive amount of humidity in the work room which is unhealthful to the operator and is rust-producing and otherwise damaging. For this reason the 120 present apparatus may be installed where it would be inconvenient or impossible to connect a stack and without causing annoyance 125 130

or damage from the escape of vapor. Furthermore the small water space surrounding the pipe 32 causes a limited amount of water to be subjected to vaporization at one time 5 so that vapor may be produced quickly when starting the apparatus with cold water without requiring an excessive current. The means for supplying the water is also easily handled, the bottles or tanks 13 being readily 10 filled and the valve therein preventing leakage or spilling before the bottle is in its operative position. While electric heating elements have been shown, elements of other description such as steam pipes, gas, etc. 15 might be employed, if desired.

In order that the operator may be able to tell at a glance which shoe has been longest treated and therefore which should be the next removed, the rack 63, as shown, has fixed 20 thereto below and parallel with its shoe supporting bar 70 a rod 71 on which is slidably an indicator such as a washer 72. This washer may be moved along the rod 71 to position it below the shoe next to be removed whenever 25 a shoe is removed or placed in position. For example, assuming that there are four shoe-receiving receptacles or treating stations *a*, *b*, *c*, *d* (Fig. 1), the rotational sequence may be, *a*, *b*, *c*, *d*, *a*, *b*, *c*, *d*, etc. On 30 starting operations the receptacles are filled in this order, the washer 72 being placed below the shoe at *a*. The shoe at *a* is then the first to be removed and either when this shoe is removed or when an untreated shoe 35 is placed at *a*, the washer is moved beneath the shoe at *b*. Similarly when the shoe is removed from *b* or an untreated one placed in that position the washer is moved under the shoe at *c*. In the same manner the washer 40 is moved in succession under the shoe at *d*, then back to the shoe at *a* and so on, clearly indicating to the operator at all times the proper shoe next to be removed.

Having thus described an embodiment of 45 this invention it should be evident that many modifications and changes might be made therein without departing from its spirit or scope as defined by the appended claims.

I claim:

50 1. In a shoe heater, means for producing dry heat, means for producing vapor simultaneously with the production of dry heat, means for supporting a partly finished shoe having a stiffener therein, means for directing the dry heat against said stiffener, and means for directing the vapor against the shoe upper.

2. In a shoe heater, a receptacle open at 55 one side for the insertion of the toe of a lasted shoe, means for conducting vapor through the sides of said receptacle into contact with the outside of the shoe, and means for simultaneously conducting dry hot air into said receptacle into contact with the 60 inner side of the pulled upper.

3. In a heater, means for simultaneously directing moist vapor against one portion of an article and dry heat against another portion, and means for preventing substantial mingling of the dry heat and moisture until 70 after contact with said article.

4. In a heater, means for simultaneously directing vapor and dry heat into a receptacle against an article, and means for preventing substantial mingling of said dry heat 75 and vapor until after they have acted on the article.

5. In a shoe heater, means for directing moisture to the upper of the toe of a pulled shoe having a stiffener therein, and means 80 for directing dry heat against the central portion of the forepart of the sole of the shoe to be deflected laterally thereby and heat the toe stiffener.

6. In a heater, a receptacle having side and lower walls and an opening at one side for the reception of an article to be heated, means for introducing a vapor into said receptacle through the side walls thereof, and means for introducing dry heat through a portion only 85 of its lower wall.

7. In a heater, a receptacle having an opening therein, means for directing vapor against one portion of an article in said receptacle, and means for simultaneously directing dry 95 heated air against another part of the article in such proportion relative to the vapor that after acting on the article and then mingling with the vapor there is substantially no escape of visible vapor from said opening.

8. In a heater, means for vaporizing water, means for cooling said vapor, a receptacle having an opening therein, means for directing the cooled vapor against an article in said receptacle, means for heating air, and means 105 for directing the heated air directly against the article in said receptacle simultaneously with the vapor and in such proportion relative to the vapor that there is substantially no escape of visible vapor from said opening. 110

9. In a shoe heater, a trough, a heating member nearly filling said trough, means for conducting water to said trough about said member to be vaporized by heat therefrom, an expansion chamber for receiving and cooling the vapor from said trough, an open sided receptacle for receiving a portion of a shoe, and means for conducting vapor from said expansion chamber into said receptacle to direct contact with the sides of said shoe portion. 115 120

10. In a shoe heater, a trough, a heating member nearly filling said trough, means for conducting water to said trough about said member to be vaporized by heat therefrom, 125 an expansion chamber for receiving and cooling the vapor from said trough, an open sided receptacle for receiving a portion of a shoe, means for conducting vapor from said expansion chamber into said receptacle into 130

contact with one part of said shoe portion, a source of dry heat, and means for conducting heat from said source to contact another part of said shoe portion simultaneously with the contacting of said one part with vapor.

11. A shoe heater comprising a substantially trough-shaped member having a series of openings through its top, a pipe nearly filling the lower portion of the trough and defining therewith a narrow annular space for the reception of water, means for supplying water to said space, a member superposed on said trough-shaped member and having a series of receptacles spaced therealong, each 10 of said receptacles being open on one side for the insertion of an article to be treated, the side walls of said receptacles having ports therethrough, a series of chambers each having communication with one of said series 15 of openings and the ports of one of said receptacles, a plate having a substantially central opening partly closing off the lower portion of each receptacle beneath said ar-

ticile, a heating element extending through said receptacles beneath said plates, and a 25 heating element extending through said pipe.

12. A device of the class described, comprising a shoe heater for simultaneously heating a plurality of shoes, a bar on which the shoes are supported, a rod arranged parallel to said bar, and an indicator slidable along said rod. 30

13. The process which comprises continuously operating more than two treating stations, placing a shoe at each of said stations in a definite order of sequence, replacing the treated shoes one by one with untreated shoes, and at the time of each replacement moving an indicator to the succeeding station of the sequence to indicate the next shoe to be replaced whereby all the shoes may receive treatment for substantially the same time. 35 40

In testimony whereof I have affixed my signature.

WILLIAM H. BAYNARD.
